(57) **CLAIM**

The ornamental design for a rotatable data cable, as shown and described.

DESCRIPTION

FIG. 1 is a front, top and right side perspective view of a rotatable data cable showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof, showing the rotatable data cable in a state of use.

The broken lines in the drawings are for the purpose of illustrating portions of the rotatable data cable that form no part of the claimed design.
